United States Patent Office

Des. 226,892

Patented May 15, 1973

226,892

MERCHANDISE DISPLAY MODULE

Michael Degennaro, New Rochelle, and Phillip Schatten,
Spring Valley, N.Y., assignors to Jonathan Leigh Inc.

Filed Nov. 12, 1971, Ser. No. 198,493

Term of patent 14 years

Int. Cl. D6—04

U.S. Cl. D6—186

FIG. 1 is an isometric view from the front, top, and right side of a merchandise display module showing our new design; and

FIG. 2 is an isometric view from the back, bottom, and left side.

We claim:

The ornamental design for a merchandise display module, substantially as shown.
